UNITED STATES PATENT OFFICE.

JESSE COBB, OF LAREDO, TEXAS.

FOLDING CRATE.

Application filed February 12, 1927. Serial No. 167,843.

This invention relates to shipping crates and more particularly folding crates for vegetables, fruit and the like, and is designed as an improvement over the crate shown 5 and described in my Patent #1,427,193, issued August 29, 1922.

A primary object of the invention is to provide a crate of this character in which maximum strength is combined with economy in manufacture.

Another object is to provide a crate of this character having strong and sufficient means for connecting the end and side members whereby they are permitted to pivot for folding and yet securely hold the parts together when in set up position.

In carrying out these objects the invention is susceptible of modification without departing from the spirit or sacrificing any of 20 the advantages of the claimed invention; there being shown in the drawings for illustrative purposes a preferred and practical form, in which:

Figure 1 represents a perspective view of 25 a crate constructed in accordance with this invention in set up position ready for use,

Fig. 2 is a horizontal section thereof,

Fig. 3 is a perspective view with the members separated and arranged in juxtaposition 30 ready for assembling,

Fig. 4 is a transverse vertical section taken on the line 4—4 of Fig. 2,

Fig. 5 is a side elevation or edge view 35 taken on a small scale showing the crate in collapsed position, and

Fig. 6 is a detail perspective view of one of the fastening elements used for connecting the sides and ends.

In the embodiment illustrated, the numerals 5 designate the sides each of which consists of upper and lower longitudinally extending side bars 6 and 7, the ends of which are secured to upright corner posts 10 by suitable fastening elements.

Connectors 20, unite the end and side members of the crate forming pintles therefor when these members are folded, and are constructed as shown in Fig. 6 from a single piece of heavy wire bent intermediate its ends to form a double membered or loop-like arm 21. This loop-like arm 21 has one member bent laterally outward at right angles as shown at 22, said finger 22 being arranged about midway the length of the arm 21, the remainder of which arm is single, as shown at 23. The free end of the finger

22 is designed to be bent laterally outward at right angles to form a securing element 24 which is bent to this position after the finger 22 has been passed through an end 60 cross beam 9 by means of which said side members are connected. The end of the member 23 of arm 21 is extended upwardly at right angles to form a pintle 25 designed to be extended through a cross bar 16 65 of one of the end members 15 as will be hereinafter more fully described. After the arm 21 has been passed through the side member which includes the post 10, the terminal thereof is bent laterally against said post as 70 shown at 27.

One of these connectors or fasteners 20 is used in each corner of the crate and operates to pivotally connect the cross bars 9 and the end members 15 with the side members 5.

The end members 15, as shown, are each composed of a plate 17 having the cross bars or cleats 16 arranged transversely across the outer faces of opposite ends thereof and secured thereto in any suitable manner. These cleats or cross bars 16 have apertures 16^a 80 extending edgewise therethrough at their opposite ends to receive the fingers 25 of the connectors 20.

The pivotally connected cross bars 9 are arranged below the end member 15 and the posts 10 and are held in operative position by the arms 22 of the connectors 20, as is shown clearly in Fig. 4.

It will thus be seen that the arms 22 and 25 which pass respectively through the cross bars 9 and the cleats 16 of the end members 15 not only operate to connect these members with the side members but also to space 95 them vertically apart a sufficient distance to receive the top and bottom members 30 and 40 as will be presently more fully described.

It will be seen from an inspection of Fig. 4 that the longitudinally extending arms 22 and 25 of the connector 20 when inserted in operative position at the corners of the crate will operate as pintles to permit the sides and ends to be folded into the position shown in Fig. 5, which folding may be effected after the top and bottom members have been removed, these members operating to hold the crate in rigid position when assembled for use, as will be presently described.

The top and bottom members 30 and 40 110 as shown, are constructed exactly alike, being composed of a plate or thin board of a

width less than the width of the crate and having secured to the outer face thereof longitudinally spaced transversely extending cleats 42, 43 and 44, which reinforce and strengthen these members and assist in holding them in operative position. As shown, these cleats are arranged one near each end of the board 41 and the other intermediate thereof, two of the cleats at one end and the intermediate cleat being of a length greater than the width of the board and adapted to extend beyond and rest on the side members of the crate when the parts are assembled. The other end member 44 is of the same length, or substantially so, of the width of the board 41, the combined thickness of said cleat 44 and the board 41 being slightly less than the distance between the cross bars 9 and the end members 15 so that this end of the closure may be inserted and slipped between said end member and cross bar in the application and removal of the closure. The thin plates or boards of the closures shown at 41 for the top and 31 for the bottom are made of yieldable material to permit the end thereof which carries the cleat 44 to be inserted between the cross beam or bar 9 and the adjacent end wall. When this narrow end of the closure has been inserted between the cross beam 9 and the end wall, the other end of the board or plate 41 may be positioned between the opposite cross beam 9 and the opposite end wall 15 and confined between them. In other words, when it is desired to apply the cover it is merely necessary to slide the narrow end thereof between one of the beams 9 and the adjacent end wall, a sufficient distance to permit the opposite end of the cover to be forced downwardly and rearwardly between the opposite beam and the opposite end wall. When so positioned, the cover will be securely held and the crate is effectively held against collapsing.

As shown in Fig. 1, when these closures are so mounted the boards constituting the body thereof will be disposed between the side members and the end cleats will abut the cross beams 9 and thus rigidly hold the crate against collapsing.

When it is desired to collapse the crate, obviously the operation is reversed, that is, the closures are removed by sliding the narrow end thereof under the cross beam 9 and then disengaging the opposite end of the closure from the corresponding cross beam and removing the closure. The side and end walls may then be folded on the pivots formed by the connectors 20 as shown in Fig. 5, and the crate may be shipped or stored occupying a minimum amount of space.

It will be obvious that a crate constructed as herein shown and described, while being collapsible, is very strong and strain resisting when in operative position, the cross

beams 9 which abut the posts 10 will support anything placed on the crate, thereby avoiding breakage of the covers which are comparatively light in construction.

Without further description it is thought that the features and advantages of the invention will be readily apparent to those skilled in the art, and it will of course be understood that changes in the form, proportion and minor details of construction may be resorted to, without departing from the spirit of the invention or its scope as claimed.

I claim:—

1. A crate comprising side walls, end walls arranged between the ends of the side walls, cross beams arranged at the ends of the side walls, and combined connectors and pivot pins one for each corner of the crate, each in the form of a unitary structure having branches extending through said end walls, said cross beams and said side walls and pivotally connecting said members to permit them to be folded.

2. A crate comprising side walls having upright end posts, end walls arranged between the ends of the side walls, cross beams arranged at the ends of the side walls and abutting the ends of the posts thereof, and combined connectors and pivot pins one for each corner of the crate, and each in the form of a unitary structure having branches extending through said end walls, said cross beams, and said side walls for pivotally connecting said end and side walls and said beams.

3. A crate having side walls, including end posts, cross beams arranged at the ends of said posts, end walls arranged between said cross beams and said side walls, and combined connectors and pivot pins arranged one at each of the corners of the crate and each in the form of a unitary structure having branches extending through the end walls and beams and through said posts whereby the end walls and side walls and the beams are pivotally connected.

4. A crate including end beams and side and end walls, the end walls having transverse cleats, combined connectors and pivots uniting said walls and each comprising a piece of heavy wire folded intermediate its ends with the folded portion extended through the side wall and its terminal bent laterally against the outer face of said wall, one of the members of said folded portion extended beyond the other and bent laterally outward at right angles and passed through one of the end wall cleats with its terminal bent laterally against said cleat the other member of said folded portion being bent at right angles in a direction opposite to the other member and extended through the adjacent cross beam with its terminal bent against said beam.
